RAIL CLAMP

Homer M. Lamb, West Frankfort, Ill., assignor
of one-half to O. L. Callahan, West Frankfort,
Ill.

Application January 24, 1939, Serial No. 252,653

3 Claims. (Cl. 238—10)

This invention relates to rail clamps and, particularly, to a clamp for securing a length of rail, commonly called the slide rail, to the end rails, referred to as permanent rails, of a mine car track when it becomes necessary to extend the track beyond the point at which it previously terminated.

In working coal mines, the mine car track is laid to a point close to the working face of the coal seam but, as extraction of coal from the seam or working face continues, the distance between the working face and track terminal increases until the distance is so great as to seriously interfere with the loading of the coal into cars on the track. This is true whether the loading is done manually or mechanically. Under such conditions, it is necessary or desirable to lengthen the track. If the rail sections used for this purpose are laid with their ends abutting the ends of the permanent rails, it is apparent that sections of different lengths would be necessary to take care of the gradually increasing distance between the working face and track terminal. Consequently, it has become the general practice to place the new rails alongside of and overlapping the end rails of the previously laid track and releasably clamp them to the permanent rails so that, by releasing the new rails, they can be slipped endwise or adjusted longitudinally of the permanent rails to lengthen the track until the new rails cease to overlap the permanent rails.

One object of the invention is to provide a rail clamp of simple construction which will effectively lock the slide rail in the desired position.

Another object is to provide a clamp which will permit of ready adjustment of the slide rail, the clamping and releasing of said rail being easily performed with the present construction.

A still further object is to provide a simple, sturdy rail-clamping member, so assembled on the cross tie of the track as to insure proper positioning of said member at all times, thus insuring easy and effective operation of the device.

Another object of the invention is to provide a clamping device integrated, so to speak, with the track cross tie, so that maximum rigidity is obtained, thus strengthening the entire structure and minimizing the possibility of any of the structural elements jarring loose under impacts imposed thereon, a condition which has to be met in the use of the present-day type of cutting and loading machines. The mounting of the several elements on the cross tie also

facilitates dismantling of the track without loss of any of the clamp structure.

With these and other objects in view, the invention consists in certain details of construction and combinations and arrangements of parts, all as will hereinafter be more fully described, and the novel features thereof particularly pointed out in the appended claims.

In the accompanying drawing—

Figure 1 is a top plan view of one end portion 10 of a cross tie and clamping device embodying the preferred embodiment of the present invention, the permanent and slide rails also being illustrated;

Fig. 2 is a longitudinal, vertical sectional view 15 on the line 2—2 of Fig. 1;

Fig. 3 is a horizontal sectional view on the line 3—3 of Fig. 2;

Fig. 4 is a transverse section on the line 4—4 of Fig. 1; and

Fig. 5 is a detail perspective view of the clamping plate.

The cross tie 10, which is preferably of metal, has a central longitudinal depression 11 therein, and mounted on the upper surface of the tie 25 are brackets 12 in which an operating lever 13 is pivoted, the lever being accommodated in said recess when in its lowered position for clamping the slide rail in place. Lever 13 comprises a handle portion and a cam-shaped extremity 13a 30 projecting from the brackets 12 toward the end of the tie for purposes which will be later described.

Near the end of the tie there is provided an abutment or stop 14, against which the rails, 35 both the permanent rail 15 and the slide rail 16, are forced and clamped. As illustrated in Fig. 2, the base of the permanent rail 15, as usual, is seated on the cross ties, but the slide rail 16 is placed with one edge of its base resting on the 40 ties and with its thread portion positioned against the web of the permanent rail. Thus, the broad bottom face of the slide rail base is disposed toward the operating lever 13.

Mounted on the tie adjacent brackets 12 are 45 guide members 17 which are offset inwardly from the sides of the tie. Preferably, each guide is of angular formation with one leg 17a of each angle spaced above the tie and extending inwardly to a point where a space forming a guide-way is 50 provided between the contiguous, inner edges. Slidable in this guide-way is a clamping plate 18 movable edgewise along the tie and also disposed edgewise with respect to the base of rail 16. To retain the plate 18 in perpendicular position on 55

the tie, said plate is formed with lateral offsets overlapping the inturned portions 17^a of the guides. Preferably, upper and lower offsets 19, 20, are provided at each side of plate 18, the lower offsets 19 engaging beneath the portions 17^a of the guides and the upper offsets 20 overlying the upper surfaces of said portions 17^a.

With the several parts in position, or assembled, the curved extremity 13^a of the operating lever engages against the face of the clamping plate 18 and forces said plate and the rails toward the abutment 14. As will be understood, the length of the end 13^a of the lever is such that, when the handle portion of said lever is depressed, as shown in Fig. 2, the rails will be securely clamped between the clamping plate 18 and abutment 14, but the slide rail can be readily adjusted lengthwise of the permanent rail merely by raising lever 13 and thus releasing the plate 20 and rails.

The several parts, such as the stop 14, guide members 17, and lever-supporting brackets 12 are all rigidly mounted, for instance, welded, on the face of the tie. As a consequence, the permanent rail is amply reinforced and there is no danger of said rail being damaged or broken by side thrusts which are necessarily present under normal working conditions and, particularly, where the present-day track-supported cutting and car-loading machines are used. Any length of slide rail can be used and, as stated, adjustment of that rail is a minor operation which can be performed without any material loss of time. Rigid attachment of the several parts also lends strength to the cross tie and, in dismantling the track, there is no possibility of losing any portion of the clamping mechanism.

By disposing the clamping plate edgewise against the base of the slide rail 16, and making said plate of a height substantially equal to the breadth of the rail base, a large area of contact is provided and, at the same time, the comparatively thin plate is amply capable of withstanding the compressive forces imposed upon it.

It will be understood that the clamping mechanism is provided at each end of the cross tie, but that only one end portion of a tie and the clamping mechanism carried thereon has been illustrated and described herein. 5

What I claim is:

1. A cross tie and clamp for slide rails comprising laterally spaced guide members on said tie, a clamping plate slidable longitudinally of the tie between said guide members, a stop fixed 10 on said tie and spaced from said plate to accommodate a permanent rail and a slide rail positioned with its tread against the permanent rail and with one edge of its base on the tie, said clamping plate being disposed edgewise toward 15 said slide rail base and said plate being of a height substantially corresponding to the width of said slide rail base to resist side thrust on the rail, and a lever pivoted on said tie engageable with the clamping plate to force the said plate, 20 together with said rails, against said stop.

2. A cross tie and clamp for side rails comprising laterally spaced guides on the tie, inwardly offset portions on said guides, a vertically disposed clamping plate slidable edgewise between said guides, lateral wings on said plate, said wings being slotted to embrace the offset portions of the guides, and means for forcing one end of said plate against the slide rail with the end of the plate engaging edgewise against said 30 rail.

3. In a tie having means for clamping a slide rail against a permanent rail with the base of the slide rail disposed vertically toward the clamping means, a clamping plate having one 35 end disposed vertically of said base and engageable edgewise against the base, the height of said end of the plate substantially corresponding to the width or height of the rail base, whereby resistance to side thrust on the rail is augmented, 40 and means on said tie for forcing said plate endwise against said rail base.
